UNITED STATES PATENT OFFICE.

CHARLES CARROLL LEIDY, OF JACKSONVILLE, ILLINOIS.

OVEN.

1,116,085.

Specification of Letters Patent.

Patented Nov. 3, 1914.

Application filed February 5, 1913. Serial No. 746,310.

To all whom it may concern:

Be it known that I, CHARLES C. LEIDY, a citizen of the United States, and a resident of Jacksonville, in the county of Morgan, 5 and State of Illinois, have invented a new and Improved Oven, of which the following is a full, clear, and exact description.

The object of the invention is to provide an inexpensive, simple and efficient oven in 10 which the contraction and expansion of the oven body structure is balanced by a granulated non-conducting material placed within the body structure of the oven.

Reference is to be had to the accompanying drawings forming a part of this specification, in which like characters of reference indicate corresponding parts in all the views, and in which—

Figure 1 is a vertical central section of 20 an embodiment of my invention, through the line 1—1 of Fig. 3; Fig. 2 is a vertical cross section on the line 2—2 of Fig. 1; Fig. 3 is a horizontal section on the line 3—3 of Fig. 2, showing the bed of granulated material; and Fig. 4 is a horizontal section on the line 4—4 of Fig. 2, showing the horizontal contraction of the products of combustion.

Referring to the drawings, 10 represents 30 a baker's oven provided with a furnace 11. The furnace is illustrated with a grate 12, but if the oven is to be used with gas or liquid fuel the furnace will be modified accordingly. The arch 13 of the furnace is 35 formed as customary, and is provided with two side openings 14 near the lower portion of the arch in each side and near the ends of the same. Through the openings 14 the products of combustion pass from 40 the furnace to the side passages 15 extending alongside the lower portion of the furnace, the passages being formed by the lower portion of the furnace and the side walls 16 of the oven. Each of the passages 45 15 has a vertical outlet 17 formed in the front end of the oven. Lying directly over the central portion of the arch 13, and longitudinally of it, is a bed of granulated non-conducting material 18, preferably dry 50 sand. The sides of the bed are formed by the tiles 19, and the top of same is covered by a tile 20, all inclosed in a body structure 21 forming part of the oven. Formed above the body 21 is a baking chamber 22, properly surrounded with passages for the products of combustion. Each of the outlets 17

has a triangular expansion 23, the longer side 24 of which forms part of a side wall of the baking chamber, the height of this triangle and the oven being the same. Each 60 of the outlets 17 leads into a horizontal passage 25 extending longitudinally of the oven, and communicating at the rear end of the oven with another horizontal passage 26 parallel to the passage 25. With the exception of the central partition 27 both of the passages 26 cover the upper surface of the top of the baking chamber, the products of combustion from these passages passing directly into the common flue 70 28 formed in the forward end of the oven.

By having a bed of dry sand in the body of the structure of the oven between the furnace and the baking chamber, the contraction produced in this portion of the 75 oven after the expansion of the same is permitted by the grains of sand forming the bed. In view of this I can dispense with metallic members, such as I beams or similar shapes within this portion of the oven, 80 which is the hottest. The presence of metallic members in this portion of the bed is not desirable, as, due to the unevenness of their coefficient of expansion and contraction cracks are formed between the furnace 85 and the baking chamber, which are very detrimental to the oven structure. The sand having substantially the same coefficient of expansion as the body structure of the oven has not the tendency to form crevices; furthermore, excessive contraction of 90 the body of the oven in this particular portion causes the grains of sand to come closer together.

To reinforce the body about the arch 95 from which metallic elements are eliminated, I use tile members 19 and 20, as shown, and which form the inclosure for the sand.

Having thus described my invention, 100 what I claim as new and desire to secure by Letters Patent is:—

1. In an oven, a furnace; a baking chamber above the furnace; a body structure separating said furnace from said chamber 105 and forming an arch above the furnace; tiles disposed longitudinally in the body and embodied therein above the central portion of the arch, said tiles forming an inclosure; and granular heat insulating material in said inclosure.

2. In an oven, a furnace; a baking chamber

ber above the furnace; a body structure separating said furnace from said chamber and comprising therein an arch above the furnace; tiles above said arch entirely embedded therein and reinforcing said body above the furnace and forming an inclosure therein; and a granular heat insulating material in said inclosure.

3. In an oven, a furnace; a baking chamber above said furnace; a body structure separating said furnace from said chamber and forming an arch above the furnace; tiles disposed longitudinally in the body

and entirely embedded therein above the central portion of the arch, said tile forming an inclosure of uniform width and substantially of uniform height from end to end of said arch; and granular heat insulating material in said inclosure. 15

In testimony whereof I have signed my name to this specification in the presence of two subscribing witnesses.

CHARLES CARROLL LEIDY.
